Primary Examiner — Mehri F Bajoul(74) *Attorney, Agent, or Firm* — Zagorin Cave LLP; Robert W. Holland(57) **CLAIM**

The ornamental design for a mobile gaming dock as shown and described.

DESCRIPTION

FIG. 1 is a front perspective view of the mobile gaming dock comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a top rear perspective view thereof; and,

FIG. 9 is a front perspective view of the mobile gaming dock in an environment of use.

Broken lines shown in the drawings illustrate portions of the mobile gaming dock and form no part of the claimed design.
